UNITED STATES PATENT OFFICE.

WILLIAM C. PEET, OF NEW YORK, N. Y., ASSIGNOR TO THE J. L. MOTT
IRON WORKS, OF SAME PLACE.

DESIGN FOR A PORCELAIN LAVATORY.

SPECIFICATION forming part of Design No. 30,135, dated February 7, 1899.

Application filed October 27, 1898. Serial No. 694,745. Term of patent 7 years.

To all whom it may concern:

Be it known that I, WILLIAM C. PEET, a citizen of the United States, residing in the city, county, and State of New York, have invented and produced a new and original Design for a Porcelain Lavatory, of which the following is a specification.

In the drawings, Figure 1 is a perspective view; and Fig. 2 is a cross-section through the bowl, slab, and skirt.

This lavatory has a bowl A, surrounded by the slab portion B, with rounded corners 2 and adjacent concave portions 3. The skirt

portion C has a contour corresponding to the edges of the slab portion, but smaller, so that the edges of such slab portion project and are rounded.

I claim as my invention—

The design for a porcelain lavatory substantially as described and represented.

Signed by me this 25th day of October, 1898.

WILLIAM C. PEET.
